UNITED STATES PATENT OFFICE.

JOHN T. HAWKINS, OF TAUNTON, MASSACHUSETTS.

FIRE-HOSE CASE OR BOX.

SPECIFICATION forming part of Letters Patent No. 311,752, dated February 3, 1885.

Application filed August 18, 1884. (No model.)

To all whom it may concern:

Be it known that I, JOHN T. HAWKINS, of Taunton, in the county of Bristol and State of Massachusetts, have invented a new and useful 5 Fire-Hose Case or Box, which invention is fully set forth and illustrated in the following specification and accompanying drawings.

The object of this invention is to provide a receptacle for the stowage of fire-hose in 10 public buildings, hotels, factories, and other buildings which shall permit of the hose being instantaneously put into position for running out in any direction without danger of kinking, cover them in out of sight and protect them from dust and dirt when not in 15 use, and form, wherever desirable, an ornamental attachment to the wall or building. In hotels, private residences, public buildings, and similar places piles or coils of hose 20 are unsightly and objectionable, and it is desirable in many such places to have a receptacle for them more or less ornamental, while in factories and other similar places it is desirable to protect the hose from dust, dirt, 25 smoke, &c.

The invention consists of a closed box or case hinged at its bottom to the wall or building, and carrying on its outer face hinged 30 braces or brackets to support the weight of the hose and case when let down, and also having three sides so hinged to its outer face that, when in position for running out the 35 hose, the hose may lie upon a mere flat surface unobstructed.

In the accompanying drawings, Figure 1 is 40 a perspective view of the case or rack let down into position ready for the running out of the hose, one side, B', of the case A being in the same position as when closed up against the wall, while the other side, B, and the top of 45 end piece, C, are dropped down, as may also be the side, B, leaving the hose free to be run out in any direction from the horizontal surface on which it lies. Fig. 2 is a perspective view of the case or rack as closed up against the wall or building. Fig. 3 is a side view of 50 the case or rack as let down in position for running out the hose, except that the sides and top are not let down.

In said figures the letter A indicates the front or face of the case as closed up against

the wall, or forming the horizontal bottom upon which the hose lies when the case is let down in position for being run out. B B' indicate side pieces hinged to the face A, and C 55 indicates an end or top piece similarly hinged to said face, the three pieces, B, B', and C being so hinged to the face A that when the case is in the position shown in Fig. 1 they may all hang in a vertical position leaving 60 the inner or upper side of A horizontal and unobstructed.

Secured to the end piece, C, on its ends, are two right-angled clamps or hooks, D, projecting over the side pieces, B B', which clamps 65 hold said pieces closed when the case is closed up against the wall. Secured also to the end or top piece, C, is a bracket, E, in which slides a rod, F, having on its outer end a ball or knob, G, and in its central part a stop-pin, H, 70 to prevent its being pulled entirely out of the bracket E. Secured to the wall is an eye or lug, I, into which the free end of the rod F enters to hold the case in position when closed up against the wall. Two triangular brackets, K K, hinged to the face A, are made, where 75 desirable, to close up against and form a part of the paneling design of the face or front of the case A when closed up against the wall, said brackets automatically dropping into the 80 positions shown in Figs. 1 and 3 by their own weight when the case is let down, as shown in Fig. 1.

S indicates the hose; N, the nozzle or hose-pipe, and M the butt or coupling projecting 85 from the wall, to which the hose is kept attached ready for use. The case is made deeper than required for the pile of hose, sufficiently to leave a space in front, as in the position shown in Fig. 1, or on top, as in position shown 90 in Fig. 2, to receive and cover in the butt or coupling M, so that the whole hose and attachments may be covered in by the case. At the bottom of the case are placed two blocks, O O, between which is a recess in which the 95 unfolded inner end of the hose lies, so that, when the case is closed up against the wall the weight of the hose will only bear upon its flattened portions, leaving such of its parts free to follow the motion of the case when let 100 down into the position shown in Fig. 1, without injury to the hose. The hose is shown

folded away in a succession of well-known return-folds, so that it cannot twist or kink in running out.

In operation, upon an alarm of fire being given it is only necessary to pull the knob G and let the case down, when the brackets K K automatically fall into place; then, by seizing the hose-pipe N and conveying it off in the desired direction the end piece, C, and side pieces, B and B', automatically fall outward into the vertical positions shown at B and C, Fig. 1, leaving the inner or upper surface of the front or face A horizontal and unobstructed.

I do not claim, broadly, a hose-support pivoted or hinged to a wall or building, so that such support may swing in a horizontal plane; but,

As of my invention, I claim—

1. A hose rack or case pivoted or hinged at its bottom to a wall, building, or other support, so as to swing in a vertical plane on said hinges or pivots, substantially as and for the purposes set forth.

2. A hose rack or case hinged or pivoted to a wall, building, or other support, so as to swing in a vertical plane on said hinges or pivots, and provided with side pieces, as B B', and an end piece, as C, hinged thereto, so that when the case or rack is placed in a horizontal position said side pieces and end piece may hang vertically downward and leave the surface supporting the hose flat and unobstructed, substantially as and for the purposes set forth.

3. In a hose rack or case hinged or pivoted to a wall, building, or other support, so as to swing in a vertical plane on said hinges or pivots, the combination of side pieces, as B B', and an end piece, as C, all hinged to a front or face piece, as A, whereby when the rack or case occupies a horizontal position said pieces may hang vertically, but may close up, forming a closed box or case when the

said rack or case is held in a vertical position, substantially as and for the purposes set forth. 45

4. A hose rack or case hinged or pivoted to a wall, building, or other support, so as to swing in a vertical plane, and provided with brackets, as K K, hinged to said rack or case, so as to automatically drop by their own weight to form supports to the said rack or case when let down into a horizontal position, substantially as and for the purposes set forth.

5. A hose rack or case hinged or pivoted to a wall, building, or other support, so as to swing in a vertical plane, and provided with hinged side pieces, as B B', a hinged top or end piece, as C, and hinged brackets or supports, as K K, substantially as and for the purposes set forth. 55 60

6. In a hose rack or case swinging in a vertical plane and provided with side pieces, as B B', and a hinged end or top piece, as C, right-angled clamps or hooks, as D D, secured to said end or top piece, by means of which the said case may be held securely closed when in the vertical position, and said pieces automatically released to hang vertically downward when said case is placed in the horizontal position, substantially as and for the purposes set forth. 65 70

7. A hose rack or case constructed to swing in a vertical plane from a wall, building, or other support, and consisting of a platform, 75 as A, hinged side pieces, as B B', a hinged end or top piece, as C, hinged brackets or supports, as K K, base-blocks, as O O, and right-angled clamps or hooks, as D D, all arranged and operating substantially as and for the purposes set forth. 80
